[57] ABSTRACT

A multiple tape dispenser comprising, a cylindrical housing having a plurality of reels of tape rotatably mounted in the housing and spaced apart in fixed relationship to each other, said housing having an edge over which the housed tape may be dispensed, and a cutting means affixed to the housing and located near the edge of the body member for cutting a length of desired tape at the point the tape is dispensed.

FIG. 1

FIG. 2

FIG. 3

FIG. 4

MULTIPLE TAPE DISPENSER

BACKGROUND OF THE INVENTION

The present invention is concerned with tape dispensing equipment, particularly hand operable multi-tape dispensers.

In the dispensing of identification tape it has been found desirable to have multiple tapes having various indicia which can be applied to a desirable object. The tape dispenser that is to be used is one that should be relatively lightweight, preferably relatively easy to manufacture.

It is an object of the present invention to describe a multiple tape dispenser which can be relatively economically reproduced.

It is an object of the present invention to also have a multiple tape dispenser having tapes of varying types and sizes capable of marking a number of varying objects.

It is also an object of the present invention to have a relatively simplified multiple tape dispenser and cutting element having easily replaceable tape rolls.

SUMMARY OF THE INVENTION

The present application is concerned with a multiple tape dispenser comprising a cylindrical body member having a plurality of reels of rotatably mounted tape such as adhesive tape, pressure sensitive tape, and the like; the cylindrical body member has an edge over which the housed tape may be dispensed, and a cutting means affixed to the body member located near the edge for cutting a length of desired tape. Preferably, the cutting edge is inserted in a rotatably mounted lid for the tape dispenser.

BRIEF DESCRIPTION OF THE DRAWINGS

FIG. 1 is a top view of a multiple tape dispenser of the present invention;

FIG. 2 is a cross section of a multiple tape dispenser of the present invention taken along the line 2-2 of FIG. 1;

FIG. 3 is a top view of an alternative embodiment of the present invention; and

FIG. 4 is a cross section of the alternative embodiment of FIG. 3 taken along the line 4-4 of FIG. 3.

DESCRIPTION OF PREFERRED EMBODIMENTS

The present invention is concerned with a multiple tape dispenser employing a plurality of reels of tape as shown in FIG. 1. The tape dispenser 1 has a housing 20 wherein the plurality of tapes 2 may be rotatably mounted. The tape rolls are preferably inserted into semicircular holding means 21 of the housing 20 wherein studs 22 of the rolls may be snapped into position thereby holding the rolls in the semicircles and allowing rotation of the rolls and dispensing the tape 23 as desired.

FIGS. 1 and 2 show an embodiment of the present invention wherein a rotatably mounted lid 3 is inserted into lid receiving means 25 which is located in the center of the housing by snap-in engagement means 26 associated with the lid. The snap-in engagement may take the form of a conical lock which engages a cooperatively designed receiving element in the center of the housing or body. The lid receiving means is shown in FIG. 2 as a center post portion of the base 37, which

will be further described below. The lid has a cutting edge 27 embedded into the lower portion of the lid. The cutting blade projects into a blade receiving space 28 located at the periphery of the housing of the body member, best shown in FIG. 2.

The tape rolls 2 rotate in fixed semicircular holding means 21 and the tape is drawn to the edge 5 of the housing member. The housing 20 is designed to hold a number of rolls of tape in fixed relationship to each other.

The axis of each tape reel is chordal to the cylindrical housing. In other words, the rolls are positioned around the cylindrical housing in circular fashion generally in an equal radial distance from the center of the housing.

When one wishes to dispense tape from the multiple tape dispenser of the present invention, one slides the lid 3 around to the appropriate spot in order to expose the desired rolls. The tape 23 from the roll 2 is extended so that the cutting blade 27 slices the tape for use. As can be seen in FIG. 2, the use of the blade receiving means recessed in the housing permits the design and use on a safe yet effective tape dispenser.

An alternate embodiment to the present invention is expressed in FIGS. 3 and 4. A housing 30 has a cutting edge, preferably a serrated edge 31, and has mounted therein a plurality of rolls 32 with tape thereon 33. The rolls are mounted in or snapped in semicircular holding means 34 of the housing. This is readily accomplished by having studs 35 on the rolls 32, best shown in FIG.

3. The studs are projections of the rolls which really provide an axis about which the rolls rotate. The cutting edge may be a serrated plastic edge of the housing or it may be a metallic edge cast or inserted into the housing.

When one wishes to dispense a tape from the multiple tape dispenser of the present invention, as shown in FIGS. 3 and 4, a lid, if desired, (not shown) may be rotated to expose the desired tape. The tape would then be extracted or pulled from the roll over the cutting edge 31 and removed from the multiple tape dispenser.

As can be seen from the above, the multiple tape dispenser can be economically reproduced from moldable plastics or from appropriately designed metallic parts, and may have a loop 29 attached thereto for the convenience of handling. In order to facilitate the cutting of the tape by either embodiment, tape holding means 36 may be utilized. The tape means would preferably be a portion of the housing so that the tape may be pulled from the cutting edge. Then when the tape is cut, the uncut tape will remain on this inclined element from which it may be extracted for subsequent tape dispensing.

Although it is not required, base means 37 of FIG. 2 and FIG. 4 may be inserted at the bottom of the multiple tape dispensing apparatus. The base may be snapped into position by appropriately designed molded plastic parts or may be screwed into a threaded portion of the housing member (not shown).

The embodiment in FIG. 2 shows that the base may have in the center thereof a lid receiving means in which the lid may be snapped into place.

As can be seen, I have devised an improved multiple tape dispenser which can be refilled with a number of varying rolls merely by removing the bottom plate (if used), passing the rolls into the housing and snapping the roll studs into the downwardly facing semicircular roll holding means.

By using this improved multiple tape dispenser, I am able with the one dispenser to identify wires or other objects with various numbers, colors, or designs.

What I claim is:

1. A multiple tape dispenser comprising;
a cylindrical housing having a plurality of reels of tape rotatably mounted in the housing and spaced apart in fixed relationship to each other, the axis of the reels being chordal to the cylindrical housing, said housing having an edge over which the housed tape may be dispensed; and
a cutting means affixed to the housing and located near the edge of the housing for cutting a length of desired tape at the point the tape is dispensed.
2. The dispenser of claim 1 further comprising a rotatable lid member which rotates to expose the desired roll.
3. The dispenser of claim 2 wherein the cutting means is comprised of a cutoff blade located in the rotatable lid member, said cutting blade projecting into

10 a blade receiving space located in the housing, said lid being adapted to rotate to cut the desired tape at the point the tape is dispensed.

15 4. The dispenser of claim 2 further comprising a base means which is affixed to the bottom of the housing and which may be removed therefrom as desired; said base means having a lid receiving means located in the center thereof, in which the lid is placed.

5. The dispenser of claim 1 wherein the cutting means is a serrated edge located at the periphery of the housing at the point the tape is dispensed.

10 6. The dispenser of claim 1 wherein the housing is further comprised of a plurality of semicircular roll holding means for holding the studs of the rolls, said studs being the axis about which the rolls rotate.

15 7. The dispenser of claim 6 wherein the semicircular roll holding means opens downwardly towards the bottom of the housing.
